Inventor

K. E. Nordin,

By Clarence A. O'Brien.

Attorney

UNITED STATES PATENT OFFICE.

KNUTE E. NORDIN, OF BERGLAND, ONTARIO, CANADA.

PLIERS.

Application filed October 12, 1925. Serial No. 62,093.

To all whom it may concern:

Be it known that I, KNUTE E. NORDIN, a citizen of the United States, residing at Bergland, in the Province of Ontario and 5 Dominion of Canada, have invented certain new and useful Improvements in Pliers, of which the following is a specification.

This invention relates to improvements in pliers, and has for its principal object to 10 provide a tool of the above mentioned character which is of such construction as to enable greater pressure to be applied on the coacting jaws in order to facilitate the turning of the object which is clamped between 15 the jaws.

A further object is to provide a tool of the above mentioned character which will not deface the object which is to be turned when a great amount of pressure is applied 20 such as frequently happens with the type of pliers now generally in use.

Another important object is to provide a tool of the above mentioned character which is simple in construction, inexpensive, and 25 furthermore adapted to the purposes for which the same is designed.

Other objects and advantages of this invention will become apparent during the course of the following description.

30 In the accompanying drawing forming part of this specification and in which like numerals are employed to designate like parts throughout the same:

Figure 1 is a view partly in elevation and partly in section of my improved pliers.

Fig. 2 is an edge elevation, and

Fig. 3 is a transverse section taken approximately on line 3—3 of Fig. 1.

In the drawing wherein for the purpose of 40 illustration is shown the preferred embodiment of my invention, the numeral 1 designates an elongated handle on the forward end of which is formed the stationary jaw 2. Cooperating with the stationary jaw 2 is the coacting movable jaw 3, the same being pivotally associated with the stationary jaw as at 4. The inner opposed faces of the jaws are provided with the cooperating cut-out 45 portions 5 and 6 to facilitate the gripping of the nut or any other object which is to be turned and the inner opposed faces of the jaws are also provided with the coacting cutting edges 7 and 8 respectively, the same being pivotally formed and attached forwardly of the pivotal connection 4.

A tail piece or extension 9 is formed on the rear end of the movable jaw 3, the same tapering gradually toward the rear end. This tail piece or extension is bifurcated as indicated at 10, and the ends of the furcations are beveled as illustrated at 11 for the purpose hereinafter to be more fully described.

Coacting with the elongated handle 1 is the operating lever 12, the forward end of 65 which is enlarged as indicated at 13. An enlargement 14 is formed on the inner side edge of the handle 1 adjacent the forward end thereof and this enlargement 14 is provided with a transversely extending groove 70 15, the same being adapted to receive the tongue 16 which extends laterally from the inner side edge of the enlarged forward end 13 of the lever 12 whereby a pivotal connection between the operating lever and the 75 intermediate portion of the handle is provided.

The forward end of the enlarged portion 13 of the operating lever 12 is reduced as 80 illustrated at 17, the reduced portion being adapted to be disposed between the furcations formed by the slot 10 provided in the tail piece 9 of the pivoted jaw 3. The outer edge of the cut-away portion 17 is provided with the shoulder 18, the same being adapted 85 to engage the outer side faces of the furcations 19 whereby the extension 9 or tail piece formed thereon on the pivoted end of the jaw 3 will be pulled inwardly toward the handle 1 so that the forward end of the 90 pivoted jaw will be moved outwardly away from the stationary jaw so that the pliers will be opened, it being understood that when the free end of the lever 12 is swung upwardly, the forward end of the lever and 95 the tail piece will move inwardly, the tongue 16 and the groove with which the same is disposed acting as a fulcrum for the lever and when the tail piece is swung to its innermost position, the beveled spacers 11 will 100 engage the inner side 6 of the adjacent portion of the handle 1.

Laterally positioned portions 20 are formed on the forward end of the reduced portion 17 adjacent the inner side edge 105 thereof and these lateral projections cooperate with the inner side faces of the furcations 19 for moving the tail piece of the pivoted jaw outwardly whereby the jaw 3 is swung on its pivot 4 inwardly to a coacting 110

relation with respect to the stationary jaw 2 so that the object to be turned will be clamped between the jaws. It is obvious that by moving the free end of the lever forwardly across the free end of the handle 1, greater pressure will be exerted on the pivoted jaw 3 so as to enable the nut to be more easily and readily loosened or tightened as the case may be without defacing the 10 nut.

A punch 21 is formed in the free end of the handle 1 for use in forming eyelets in belting or the like and through which lacing is adapted to extend. An outlet 22 is 15 provided for the particles of leather which have been removed from the belting by the punch 21 as clearly illustrated in Fig. 1.

The simplicity in which my improved pliers is constructed, enables the same to be 20 readily assembled and the parts will at all times be positive and efficient in their operation. The cutting edges 7 and 8 permit the tool to be used as a cutting implement whenever necessary thus obviating the necessity 25 of having to use an independent tool for cutting purposes.

While I have shown the preferred embodiment of my invention, it is to be understood that various changes in the size, shape and 30 arrangement of parts may be resorted to without departing from the spirit or sacrificing any of the advantages of the appended claim.

Having thus described my invention, what I claim as new is:—

A tool of the class described comprising an elongated handle, a stationary jaw formed on the forward end thereof, a coacting jaw pivotally associated with the stationary jaw, a tail piece formed on the rear 40 end of the pivoted jaw, said tail piece being bifurcated, a lever, means for pivotally connecting the forward portion of said lever to the intermediate portion of said handle, the forward end of said lever being reduced, 45 said reduced portion being disposed within said bifurcation formed in the tail piece of the pivoted jaw, shoulders formed on the reduced portion of the lever adjacent the outer side thereof for cooperation with the outer 50 side faces of the furcations of said tail piece for effecting the inward swinging movement of the tail piece when the lever is swung outwardly, and lateral projections formed on the reduced portion of the lever adjacent 55 the inner side thereof and adapted for engagement with the inner side faces of the furcations to effect the outward swinging movement of the tail piece and the simultaneous inward swinging movement of the 60 pivoted jaw into coacting relation with the stationary jaw when the lever is swung inwardly.

In testimony whereof I affix my signature.

KNUTE E. NORDIN.
